Primary Examiner—Philip S. Hyder*Attorney, Agent, or Firm*—Webb Ziesenheim Bruening Logsdon Orkin & Hanson[57] **CLAIM**

The ornamental design for a drain nut pliers, as shown and described.

DESCRIPTION

FIG. 1 is a perspective view of the drain nut pliers according to my new design;

FIG. 2 is a top view thereof, the opposite bottom view of which is a mirror image;

FIG. 3 is a right side view thereof, the opposite side view of which is a mirror image;

FIG. 4 is a front view thereof;

FIG. 5 is a rear view thereof;

FIG. 6 is a top perspective view of the drain nut pliers according to a second embodiment of my new design;

FIG. 7 is a bottom perspective view thereof;

FIG. 8 is a top view thereof;

FIG. 9 is a bottom view thereof;

FIG. 10 is a right side view, thereof the opposite of which is a mirror image;

FIG. 11 is a front view thereof; and,

FIG. 12 is a rear view thereof.
